UNITED STATES PATENT OFFICE.

HENRY E. MUCHNIC, OF ATCHISON, KANSAS.

RAILWAY-CROSSING STRUCTURE.

Application filed November 14, 1923. Serial No. 674,638.

REISSUED

To all whom it may concern:

Be it known that I, HENRY E. MUCHNIC, a citizen of the United States, residing at Atchison, in the county of Atchison and 5 State of Kansas, have invented certain new and useful Improvements in Railway-Crossing Structures, of which the following is a specification.

This invention relates to improvements 10 in railway crossing structures, and is a modification of the structure originally shown and claimed in my prior Patent 1,154,534, patented September 21, 1915.

In the present form I have provided approach plates coactable with the outside of 15 the rails of a track and an intermediate plate constructed to bridge the space between the rails, these elements being varied in form and arrangement to accommodate 20 various track layouts. In the present embodiment, I have constructed my plates to permit securing of the intermediate plate in position between the rails without spikes or other through fastening means, permitting 25 disposition of the plate without regard to the location of the cross-ties which is necessary where through spikes or the like are used.

Another object of my invention is to provide 30 a structure of this character which may be positioned without interference from the rail joints or tie-plates, this being accomplished by the provision of integral lugs which may be knocked or chipped off from 35 the supporting flanges.

Another object consists in the provision 40 of an approach plate which will interlock with or engage a track rail so that with the assistance of ordinary spikes driven in the ties at the side of the plate opposite to the rail the approach plate may be held securely in position.

The purpose of these plates is to carry a 45 roadway or other crossing over a track in such wise that access to the track or roadbed may be readily had in order to permit the crossing of the track to be laid with a minimum of expense and labor, eliminating the use of planks, concrete or the like now 50 in general use.

These and other objects will be more fully set forth and described in the following specification and shown in the accompanying drawing, in which

55 Fig. 1 is a plan view showing my railway crossing as applied to a single track.

Fig. 2 is a vertical section along line 2--2 of Fig. 1.

In the drawings, 10 designates, generally, the ordinary T-shaped rails having the head 60 portions 10^a and the base flanges 10^b and 10^c extending to outside of the central web 10^d. These rails 10 are carried on the usual transverse sleepers or ties 12. In the form shown, the track is secured to ties 12 by tie- 65 plates 13 of conventional construction, and I have illustrated such a rail joint, generally indicated by numeral 14, also of conventional construction, and including a chair or tie plate member.

Extending between the rails 10 is the intermediate plate member, generally indicated by numeral 15, and comprising a body or supporting portion 15^a provided with cross ribs or corrugations 15^b to eliminate 70 danger of slipping. Extending downwardly and outwardly from the upper supporting portions 15^a are the side flanges 15^c. Between the side flanges and formed integral therewith and with the upper portion 15^a are the strengthening ribs 15^d serving 75 to strengthen and re-inforce the structure. At their supporting edges the flanges 15^c are provided with lugs 15^e (see Fig. 1) which may be broken or chipped off, as 80 desired, thus permitting the flanges to rest upon the base of the rails without interference from rail joints or tie plate members, the lugs being broken away to accommodate such members, as shown, for example, in Fig. 2.

To secure the intermediate plate 15 between the rails, I provide wedges or filler blocks 17 of wood, or the like, which may be slid longitudinally of the rail into position beneath the head of the rail, these members 17 coacting with the rail heads and the flanges 15^c to prevent vertical displacement of the supporting plate 15, the lugs 15^e preventing movement longitudinally of the track.

In use with a single track, as shown in the drawing, I provide an approach plate 20 at the outer side of each rail, these approach plates being provided with the upper corrugated supporting surfaces 20^a and the vertical depending flanges 20^b and 20^c, the former having an angularly directed base plate 20^d. Intermediate the ends of the approach plate 20 the flange 20^c is inset to provide a recess 20^e for the accommodation of the rail joint or similar member. At

the sides of the recess 20° the flange 20° is projected outwardly of the plate 20 to fit beneath and engage the rail head 10^a, as indicated at 20'. The portions 20^t of flange 5 20° are continued downwardly to rest upon the base plate of a rail and are maintained in position by spikes 25 or the like engaging the portions 20^d of flanges 20° to prevent outward displacement should the roadway 10 fail to prevent such displacement.

It will be obvious by the structure above described that I am enabled to provide a strong crossing between and at the sides of a track which may be economically constructed of cast iron and which is capable of being quickly removed for replacement or access to the road-bed in contra-distinction to planks, concrete, or the like now generally used. It will also be apparent that these 20 plate members may be laid without interference from the rail joint, tie-plates, or the like, thus permitting ready application to existing track-ways.

I do not wish to be restricted to the form 25 shown and described, except as defined in the appended claims.

What I claim is:

1. In combination with a pair of rails, a plate member extending therebetween, 30 said plate having depending supporting flanges, and wedge members inserted between each rail and the adjacent flange.

2. In combination with a pair of rails, a plate member extending therebetween, 35 said plate having depending outwardly inclined supporting flanges, and wedge members inserted between each of said rails and the adjacent flange.

3. An article of manufacture comprising a railway crossing plate having an upper 40 supporting portion, and depending supporting flanges, said flanges being provided with removable lugs at their supporting edges.

4. In combination with a pair of rails having base flanges, and a plate member 45 extending between said rails, said plate member having depending supporting flanges resting upon said rail flanges, and members coacting with said rails and said plate members to prevent vertical displacement of said 50 plate members.

5. In combination with a pair of rails having base flanges, and a plate member extending between said rails, said plate member having depending supporting flanges 55 resting upon said rail flanges, and means coacting with said rails and said plate members to prevent vertical displacement of said plate members, said last named means comprising wedges located beneath the heads 60 of said rails.

In testimony whereof, I have subscribed my name.

HENRY E. MUCHNIC.
